Primary Examiner — Gino Colan(74) *Attorney, Agent, or Firm* — Egbert Law Offices, PLLC(57) **CLAIM**

The ornamental design for a component of a tripod stepladder, as shown and described.

DESCRIPTION

FIG. 1 is an upper perspective view of a component of a tripod stepladder showing my new design.

FIG. 2 is a front view thereof;

FIG. 3 is a rear view thereof;

FIG. 4 is a top view thereof;

FIG. 5 is a bottom view thereof;

FIG. 6 is a side view thereof;

FIG. 7 is an opposite side view thereof; and,

FIG. 8 is a lower perspective view showing the component of a tripod stepladder in use on a tripod ladder. The broken lines showing a tripod ladder in FIG. 8 are included for the purpose of illustrating environment and form no part of the claimed design.
